UNITED STATES PATENT OFFICE.

ROBERT S. BOOTH, OF WATERBURY, CONNECTICUT, ASSIGNOR TO BERBECKER & ROWLAND MANUFACTURING COMPANY, OF WATERVILLE, CONNECTICUT, A CORPORATION OF CONNECTICUT.

SLIDE FOR FURNITURE AND THE LIKE.

Application filed November 29, 1921. Serial No. 518,535.

To all whom it may concern:

Be it known that I, ROBERT S. BOOTH, a citizen of the United States, residing in Waterbury, in the county of New Haven, in the State of Connecticut, have invented certain new and useful Improvements in Slides for Furniture and the like, of which the following is a specification.

The invention relates to an improvement in antifriction slides for furniture and the like.

It has been proposed heretofore to provide the legs or supports of chairs, tables and other articles of furniture with anti-friction slides or tips to serve in the place of casters. Such slides or tips have gone into extensive use and their advantage over casters for certain purposes is well known. One form of such slide or tip consists of a sheet metal disc having a smooth, convex bottom surface provided with an upturned rim from which project a plurality of pointed prongs which are adapted to be driven into the bottom of the legs or supports of the article of furniture. By reason of its peculiar construction, this form of slide must be of relatively heavy and stiff material to prevent its deformation while it is being attached to the article of furniture. Moreover, such is the shape of the slide that it is relatively expensive to manufacture. Another form of slide consists of a disc having a smooth, convex bottom surface and provided with a centrally arranged prong or shank which is adapted to be driven into the bottom of the leg or support of the article of furniture. This form of slide possesses the advantage of being readily attached to the article of furniture, but as heretofore constructed it has also been relatively expensive to manufacture. The object of the present invention is to produce an improved anti-friction slide or tip of the centrally arranged prong or shank type, which will be relatively cheap to manufacture and will be efficient and durable in use. To the accomplishment of this object the invention consists in the improved anti-friction slide for furniture hereinafter described and particularly pointed out in the claims.

The preferred form of the invention is shown in the accompanying drawings in which Fig. 1 is a bottom plan of the im-

proved slide or tip; Fig. 2 is a section taken on the line 2—2 of Fig. 1; and Fig. 3 is a side elevation of the slide showing its attachment to the bottom of the leg of an article of furniture.

The improved anti-friction slide or tip for furniture and the like as illustrated in the drawings, consists of a disc or slide proper 5 and a prong or shank 6 by which the slide is attached to the bottom of the leg or support of the article of furniture, as shown in Fig. 3. The prong or shank 6 is securely fastened to the center of the upper surface 7 of the slide, as shown in Fig. 2, by forcing a portion of the upper surface of the slide over the head 8 of the shank in any usual or well known manner. Inasmuch as a portion of the central part of the slide is used to overlap the head of the prong or shank in securing the latter to the slide, the central part of the slide is necessarily thinner than the outer part or rim of the slide. Hence, the central part of the slide consisting of a convex bearing surface and a centrally arranged attaching shank is deprived of some of its wearing surface.

To prevent the relative thin central portion of the slide where the shank is secured thereto from being subjected to wear and therefore exposed to the liability of the slide wearing through to the head of the shank, the present invention contemplates a slide or tip having an annular bottom or bearing surface. By providing an annular bearing surface, a maximum of durability is secured without impairment of efficiency or interference with ease of moving the article of furniture. That is to say, the greater bearing surface resulting by reason of its annular form involves no appreciable greater friction than the usual convex bearing surface. The annular bearing surface is formed as a convexity 10 in the outer part or rim 11 of the slide. The annular convexity or bearing surface 10 surrounds a central, depressed portion 12, as shown in Fig. 2. The whole slide is adapted for manufacture on an automatic machine. By providing the slide with the thickened annular convexity 10 as a bearing surface and by depressing the central portion 12 of the slide so that it is not exposed to wear, a slide of maximum durability is produced. At the same time,

the provision of the centrally arranged prong or shank 6 insures ready attachment of the slide to the leg or support of the article of furniture. Folding over a part 5 of the slide onto the head of the shank to secure the latter to the slide conduces to cheapness of manufacture. Thus there is produced by the present invention an anti-friction slide or tip for furniture which is 10 efficient and durable in use and relatively cheap to manufacture.

Having thus described the invention what is claimed as new is:—

1. The combination with an article of furniture, of a slide member connected thereto, said slide member comprising a disk having an annular portion providing a convexity designed to form an annular bearing surface, the upper edge of said annular portion being adapted to contact the article of furniture for receiving the loads at all points on said upper edge, said disk being provided with a central portion forming a convexity, the upper surface of which 15 is spaced from the article of furniture and the undersurface of which is spaced from the bearing surface and from the floor, and means involving a centrally located member having one end connected to the central portion of the disk forming the convexity, and the other end secured to the article of furniture, said member being adapted to transmit a portion of the load to the central convexity of the disk.
2. The combination with an article of furniture, of a slide member connected thereto, said slide member comprising a disk having an annular portion providing a convexity designed to form an annular bearing surface, the upper edge of said annular portion being adapted to contact the article of furniture and receive loads at all points 20 on said edge, said disk being provided with a central portion forming a convexity, the upper surface of which is spaced from the article of furniture and the undersurface of which is spaced from the bearing surface and from the floor, and a pin secured 25 to the slide member with its shank portion

projecting from the upper surface of the 50 portion of the disk forming the central convexity for engagement with the article of furniture, and its head portion contacting the upper surface of said central convex portion, said central convex portion 55 acting to support and retain the pin in position.

3. As an article of manufacture, a slide for furniture and the like comprising a disk having a portion providing an annular convexity, the bottom face of which forms a bearing surface and the outer surrounding edge of which is adapted to contact the article of furniture and provide a support therefor at all points on said edge for receiving the loads, said disk being formed with a central portion forming a convexity, the upper face of which is spaced from the article of furniture and the underface of which is spaced from the annular bearing surface, and a pin connected to said central portion, said pin being supported against lateral movement by adjacent portions of the upper surface of the central convexity and having its head portion resting thereon for transmitting a portion of the vertical loads to said central convex portion.

4. As an article of manufacture, a slide for furniture and the like comprising a disk having a portion providing an annular convexity, the bottom face of which forms a bearing surface and the outer surrounding edge of which is adapted to contact the article of furniture and provide a support therefor at all points on said edge for receiving vertical loads, said disk being provided with a central portion forming a convexity, the upper face of which is spaced from the article of manufacture and the underface of which is spaced from the annular bearing surface, an attaching pin adapted to transmit both the vertical and lateral loads to the disk, and means including a bendable portion of the disk for connecting said pin to the upper surface of said central convex portion.

ROBERT S. BOOTH.
